UNITED STATES PATENT OFFICE.

JOHN Q. SHERMAN, OF DAYTON, OHIO.

MANIFOLDING DEVICE.

Application filed June 23, 1922. Serial No. 570,391.

To all whom it may concern:

Be it known that I, JOHN Q. SHERMAN, a citizen of the United States, and a resident of Dayton, in the county of Montgomery and State of Ohio, have invented certain new and useful Improvements in Manifolding Devices, of which the following is a full, clear, and exact description, reference being had to the accompanying drawings, forming part of this specification.

My invention relates to manifolding devices and more particularly to a certain new method of forming manifolding copies with an impressed type face.

15 The method referred to consists essentially in bringing an embossed element against one face of an assembly of pins, which are independently movable, and thereby projecting the pointed ends of the 20 pins, constituting the other face of the assembly, into the webs of paper to be marked. In connection with the pin mounting, this method includes some sort of inking method for providing a film of ink on the penetrating surface of the pin points, so that the tiny holes made by each pin will be outlined by the ink, thereby providing a legible copy on each sheet that the pin points pass through.

25 This method is covered in its broader aspects in another application filed by me, Serial No. 560,237, filed May 11, 1922, wherein the specific form shown embodies a relatively fixed chase formed of a pin assembly 30 and in which a typewriter and its support are moved bodily for line spacing, and the machine itself or the carriage thereof moved laterally for letter spacing, so as to make the entire imprint in the pin assembly before returning the pins to normal position 40 or in other words "rectifying" the assembly.

In the present invention it is my object to provide a device for use particularly 45 with typewriters, wherein the pin assembly is small and carried by the typewriter and the rectification takes place each time an imprint is made.

This object and other attendant advantages I accomplish by that certain construction and arrangement of parts to be herein-after more specifically pointed out and claimed.

In the drawings,

55 Figure 1 is a top plan view of a pin assembly and holder much enlarged.

Figure 2 is a side elevation thereof made on the same scale as Figure 1.

Figure 3 is a detail side elevation and plan of one of the pins.

60 Figure 4 is a side elevation and plan of a preferred form of type.

Figure 5 is a side elevation showing a typewriter and flat bed support on a much smaller scale than Figure 1.

65 Figure 6 is a view of a characteristic imprint made by the device on all copies, this imprint being on a scale larger than normal, but smaller than of Figure 1.

Figure 7 is a front elevation of an ordinary typewriter showing my invention.

70 Figure 8 is a detail side view of part of the carriage of an ordinary typewriter showing a modified use of the invention over Figure 7.

75 Figure 9 is an end view of the platen and the device shown in Figure 8.

Referring to the parts of a complete machine as indicated in Figure 5, which illustrates an Elliot Fisher machine, there is 80 shown a support 1, over which it will be understood a number of webs of paper are laid, or, if desired, fed from storage rolls 2. On rails at the sides of this support is mounted a typewriter 3 having type bars 85 4 and type 5.

On a lower cross bar of the typewriter and supported in a position to come at the printing point of the type bars of the machine is a frame 6, which contains the pin 90 assembly. This frame moves with the typewriter in this particular form of construction.

The pins are preferably of fine gauge tempered wire having cylindrical shanks 7, 95 eyes 8, as in a needle, and tapered points 9. The pointed ends 9 are preferably grooved, as at 10, to leave an ink space above the points.

These pins are assembled within the 100 frame 6 and held fairly tightly by means of cross bars 11 lying intermediate the ends of the frame.

At the bottom of the frame is mounted a foraminated plate or screen 12, which is 105 arranged with the holes therein placed to receive the pin points. An inking pad 13 is placed beneath this screen and a second screen 12a mounted beneath the pad, all three members being suitably held in the 110 frame.

There are a series of fine, flexible wires 14

- strung through the eye in each pin, these wires passing through small holes in the bars 11 and held in the cross arms 15. By pulling outwardly on the two cross arms, 5 the wires are pulled straight, and all pins brought to the same level. The eyes 8 are oblong so as to permit the wires 14 being depressed by certain pins without affecting other pins.
- 10 When any one pin or series of pins are forced down, as by bringing a type face against the assembly, it is desired that the wires give sufficiently that the selected pins will move down.
- 15 Thus the cross arms are provided with hooks 16 by means of which they are secured to fairly heavy springs 17. The springs 17 are hooked to brackets 18 mounted on the end bars of the frame.
- 20 As a preferred form of type I provide each type bar with a type having a base 19 and a thin, highly raised letter or symbol 20. I prefer that the symbol or letter be formed of a piece which is of less thickness 25 than the exposed ends of the pins, so as to obtain finest lineation.
- As so constructed my device operates as follows: The operator brings the typewriter over the paper which it is desired to mark, 30 there being as many webs of paper as desired. He then proceeds to write in the usual manner, with the result of each type bar bringing its type face down against the pin assembly and forcing such of the pins as 35 the edges of the type engages into depressed position.
- The points of the pins, inked from the pad, will pass down into and through the paper below and form a series of small 40 holes in each web, said holes arranged to correspond to the type. The type bar then flies back and the cross arms will pull the wires which were put under stress by the movement of the pins outwardly again, so as to 45 return the pins acted upon to normal position.
- The arrangement should be such that the pins follow up the type as it rises from the assembly.
- 50 As in the other application referred to the pin motion is limited by the taper on the points thereof engaging in the screen 12 before the cylindrical portions of the pins have reached the foraminations, or it may also be 55 limited by limiting the stroke of the type carrying bars.
- The device shown in Figure 7 shows an ordinary typewriter 30 having mounted on the usual ribbon holder guide plate, the pin 60 chase 6.
- Where it is desired to carry the pin chase with the carriage of the typewriter, the usual reciprocating ribbon holder may be replaced by a member for effecting the rectification.
- 65 I have shown the typewriter carriage frame part 31 in which is retained the rotary platen 32. The pin chase 33 will be long and narrow instead of square, but otherwise will respond to Figure 1. In addition to the bars 15 of the chase being connected to 70 springs 17, small wires 34 will be connected to each hook 16, and brought out through the end bars of the frame 6. These wires will be connected together and will be guided by pulleys or eye screws 35, so that 75 the wire extends across the face of the pin chase in the path of the ribbon guide, if it were to be used. Instead of this guide I employ a bar 36, which reciprocates between the wire and the chase in time with the type bars, this bar having a stronger spring return than the usual ribbon guide. As the bar moves down after a printing action, the hooks 37 on the end thereof give the wire a 80 pull, which adds to the effect of the springs 85 in rectifying.
- There may be various ways of forming the small chase for the pin assembly and rectifying the pin position, and I have not attempted to describe more than several of the 90 ways that can be used for this purpose. Electrical induction, magnetized or electrically energized plates or type may also be successfully used for rectifying purposes.
- Having thus described my invention, what I claim as new and desire to secure by Letters Patent, is:—
1. In a device of the character described, in combination with a typewriter, of an assembly of pins, means for retaining said assembly in position between the type of the typewriter and the material to be printed, said means being mounted on the typewriter. 95
- 100 2. In a device of the character described, in combination with a typewriter, of an assembly of pins, means for retaining said assembly in position between the type of the typewriter and the material to be printed, said means being mounted on the typewriter, and means for returning said pins to a normal position after having been acted on by the said type. 105
- 110 3. In a device of the character described, the combination with a typewriter, of an assembly of pins, means for retaining said assembly in position between the type and the paper to be printed at the printing point of the typewriter, said means being adapted to permit individual movement of the pins, said retaining means being mounted on the typewriter. 115
- 120 4. In a device of the character described, the combination with a typewriter, of an assembly of pins, means for retaining said assembly in position at the printing point of the typewriter between the type of the typewriter and the paper to be printed, said means being adapted to permit individual movement of the pins, said retaining means being mounted on the typewriter, and 125
- 130 65 I have shown the typewriter carriage

means for returning each pin to normal undepressed position after action on the assembly by the typewriter.

5. In combination with a typewriter, a chase mounted thereon, said chase being located at the printing point of the typewriter, an assembly of pins in said chase, said pins being free for independent movement under influence of the face of a type member of the typewriter, and automatic means acting upon each pin independently, adapted to return it when freed from contact with such type face to its normal undepressed position.

10 6. In a device of the character described, the combination with a typewriter, of an assembly of pins, means for retaining said assembly in position at the printing point of the typewriter between the type of the typewriter and the paper to be printed, said means being adapted to permit individual movement of the pins, said retaining means being mounted on the typewriter, and means for returning each pin to normal undepressed position after action on the assembly by the typewriter, said means including a part movable by the printing operation of the typewriter.

20 7. In combination with a typewriter, a chase mounted thereon, said chase being located at the printing point of the typewriter, an assembly of pins in said chase, said pins being free for independent movement under influence of the face of a type member of the typewriter, and automatic

means acting upon each pin independently, adapted to return it when freed from contact with such type face to its normal undepressed position, said means comprising a wire strung through an aperture in each pin, and means for pulling on said wire.

8. A pin chase for use with typewriters, comprising a frame, slide bars in said frame, means for pulling said slide bars apart, an assembly of pins, means within the frame for holding said pins together, with freedom for independent movement, and wires or the like passing through apertures in each pin, said wires being connected to the slide bars, for the purpose described.

9. A pin chase for use with typewriters, comprising a frame, slide bars in said frame, means for pulling said slide bars apart, an assembly of pins, means within the frame for holding said pins together, with freedom for independent movement, and wires or the like passing through apertures in each pin, said wires being connected to the slide bars, and said apertures being oblong, for the purpose described.

10. In a device of the character described, a frame, an assembly of pins, means for retaining within said frame the assembly of pins so as to have freedom for individual movement, and means for returning each pin to normal position after having been moved, said means comprising wires or the like and elongated eyes in the pins through which the wires pass.

JOHN Q. SHERMAN.
